US00D910438S

(12) **United States Design Patent** (10) **Patent No.:** **US D910,438 S**
(45) **Date of Patent:** **** Feb. 16, 2021**

(54) **PLASTIC FOOD CONTAINER**

(71) Applicant: **Anchor Packaging, LLC**, St. Louis, MO (US)

(72) Inventors: **Kevin Krueger**, Fenton, MO (US); **Mike Pohlman**, Valley Park, MO (US)

(73) Assignee: **Anchor Packaging, LLC**, St. Louis, MO (US)

(**) Term: **15 Years**

(21) Appl. No.: **29/695,418**

(22) Filed: **Jun. 19, 2019**

(51) LOC (13) Cl. **09-03**

(52) U.S. Cl. .... **USPC D9/425**

(57) **CLAIM**

The ornamental design for a plastic food container, as shown and described.

DESCRIPTION

FIG. 1 is a top, front perspective view of a plastic food container, showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is an exploded top, front perspective view thereof;

FIG. 9 is a front elevation view thereof, shown without the base for ease of illustration;

FIG. 10 is a rear elevation view thereof, shown without the base for ease of illustration;

FIG. 11 is a left side elevation view thereof, shown without the base for ease of illustration;

FIG. 12 is a right side elevation view thereof, shown without the base for ease of illustration;

FIG. 13 is a top plan view thereof, shown without the base for ease of illustration;

FIG. 14 is a bottom plan view thereof, shown without the base for ease of illustration;

FIG. 15 is a front elevation view thereof, shown without the lid for ease of illustration;

FIG. 16 is a rear elevation view thereof, shown without the lid for ease of illustration;

FIG. 17 is a left side elevation view thereof, shown without the lid for ease of illustration;

FIG. 18 is a right side elevation view thereof, shown without the lid for ease of illustration;

FIG. 19 is a top plan view thereof, shown without the lid for ease of illustration; and,

FIG. 20 is a bottom plan view thereof, shown without the lid for ease of illustration.
